COMBINATION CONTACT AND TERMINAL
FOR ELECTRIC SWITCHES

Edward N. Jacobi, Milwaukee, Wis., assignor to
Briggs & Stratton Corporation, Milwaukee,
Wis., a corporation of Delaware

Application July 19, 1944, Serial No. 545,627

5 Claims. (Cl. 200—166)

This invention relates to electric switches and refers particularly to small automotive switches which are generally, though not necessarily, actuated by key controlled lock mechanisms. Switches of this type are illustrated in Patents Nos. 1,842,451 and 1,912,982, issued to E. N. Jacobi, January 26, 1932 and June 6, 1933, respectively.

While the invention broadly concerns switches of this type, it has particular reference to the wire terminals and stationary contacts thereof. One of the features of these switches is that the switch mechanism is mounted in the inner end portion of a cylindrical lock body or casing adapted to be secured to a panel by a clamping nut threaded on the body or casing and cooperating with a flange or shoulder on its front end. The body or casing is of necessity small in diameter and the clamping nut is fitted thereon by being passed over its inner or rear end.

The terminal head of the switch closes the rear end of the body or casing and the wire terminals are secured to this head to project endwise therefrom.

One of the objects of the invention is to so construct the terminals that while the wire leads are securely gripped, all portions of the terminals and the attachment of the wires still lie fully within the circumference of the lock body or casing so that the clamping nut may be freely applied or removed after the wires have been secured in position. This, of course, is a decided advantage in that it facilitates the installation of the switches. By virtue of this construction the attachment of the wires may be effected under circumstances considerably more convenient than if they had to be connected after the switch was mounted in its position of use.

Another object of this invention is to provide a wire terminal of the character described which not only provides an improved manner of securing the wire leads to the stationary contact members of the switch, but also serves to secure the stationary contacts in position on the terminal head.

In view of the relatively small size of switches of this type and the consequently small travel of the movable contactor the heads of the stationary contact members must necessarily be small to insure the proper electrical clearance. Still these contact members should have enlarged heads to hold the members against being pulled out of the terminal head. As a result, the shanks of the stationary contact members, which protrude through the terminal head, are of limited diameter. It is therefore another object of the pres-

ent invention to obviate this disadvantage through the provision of means not limited by the diameter of the head on the contact member for gripping the wire.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a side view of an electric switch embodying this invention, a part thereof being broken away and in section;

Figure 2 is an exploded perspective view illustrating the various parts of the combination stationary contact and wire terminal;

Figure 3 is an enlarged longitudinal sectional view through the terminal illustrating the same in its completely assembled state; and

Figure 4 is a view illustrating the manner in which the terminals are clinched to effect permanent securing of the contacts and wires.

Referring now particularly to the accompanying drawing in which like numerals indicate like parts, the numeral 5 designates the casing or body of a lock switch within which the switch mechanism indicated generally by the numeral 6 is mounted to be actuated by a rotatable tumbler controlled cylinder 7 upon the insertion of a proper key 8.

The front end 9 of the casing is flanged to provide a shoulder which bears against the front face of the mounting panel (not shown) and thus cooperates with a clamping nut 10 to mount the casing or body on the panel. The nut 10 is adapted to be passed over the inner rear end of the casing or body.

The switch mechanism comprises a movable contactor 11 connected with the lock cylinder 7 in any conventional manner to be rotated to and from a position bridging a pair of stationary contacts 12. The stationary contacts are mounted on an insulated terminal head 13 which is secured in and closes the open rear end of the casing or body.

The two stationary contacts, which are identical, are provided by the heads 14 of headed cy-

lindrical pins or contact members 15. The shank of each of these members is tubular and projects through a hole 16 in the terminal head. The inner end of this hole is counterbored to receive the head 14 so that the contact surface rises but slightly above the inner face of the terminal head. The heads 14 also secure the pins or contact members 15 against being pulled out of the terminal head.

Telescoped over the tubular shank of each of the pins or contact members 15 is a sleeve 17. One end of this sleeve bears firmly against the outer face of the insulated terminal head and its opposite end portion projects a substantial distance beyond the pin or contact member 15. Inserted into each assembled sleeve and pin is an insulated wire 18, the insulation having been removed from the extreme end portion of the wire which enters the tubular shank of the pin or contact member 15, while the insulation extends into the sleeve 17.

Sleeve 17 may be counterbored to a larger diameter in order to take thicker insulation diameter of wire 18. Sleeve 17 may also be reduced by turning to a smaller diameter at the neck 20, so that the metal at this point may be corrugated properly to produce a firm clinch and an intimate contact with the wire.

The assembled sleeves, pins and wires are transversely deformed by being clinched between complementary dies 19 of an arbor press, as shown in Figure 4. In this manner a localized portion 20 of each terminal assembly is deformed from its normal round transverse shape into an oval shape thus effecting a mutual interlocking relationship which firmly locks the parts together and secures the contact members or pins 15 in position on the terminal head.

In the clinching operation care must be taken that the sleeve bears solidly against the terminal head, and to insure a solid grip the ends of the sleeves are preferably beveled to provide sharp edges which bite into the terminal head during the clinching operation. The outer ends of the contact members or pins 15 are also preferably beveled to provide sharp edges to bite into the ends of the insulation on the wires.

The outermost ends of the sleeves, which are also beveled and have sharp edges, are clinched inwardly around their entire perimeters as at 21 to grip the insulation and hold the same against shifting.

From the foregoing description, taken in connection with the accompanying drawing, it will be readily apparent to those skilled in the art that this invention provides a simple but highly effective terminal construction for small electric switches and that it provides a strong, solid connection between the wire and stationary contact of the switch without in anywise interfering with the passage of the clamping nut onto and off of the casing or body. Thus it is possible to attach adequate lengths of wire to the switch at the factory and thereby eliminate the difficulties attending the attachment of wires after a switch of this type is mounted in place.

What I claim as my invention is:

1. A combination contact and wire terminal for electric switches comprising: an insulated terminal head having a hole therethrough; a headed contact member having an elongated tubular shank received in the hole and projecting beyond the terminal head to provide a wire terminal, the head on the contact member holding said contact member against being pulled through

the terminal head; a wire lead having its end portion received in the tubular shank; a sleeve fitted over the shank of the contact member and bearing firmly against the insulated terminal head; and said sleeve and tubular shank being transversely clinched to the extent that the wire within the shank of the contact is deformed and secured to the contact member.

2. In an electric switch: an insulated terminal head having a hole therethrough; a contact member having a tubular shank projecting through said hole; means for limiting endwise movement of the contact member in one direction; a wire lead having its end received in the tubular shank; and a sleeve fitted over the shank of the contact member and bearing firmly against the terminal head; said sleeve, shank and wire being transversely clinched into a deformed cross sectional shape whereby said parts are firmly secured against movement with respect to each other with the sleeve bearing against the terminal head to secure the contact member in place, and a good electrical connection is established between the contact member and the wire.

3. In an electrical switch: an insulated terminal head having a hole therethrough with a counterbore opening to one face; a headed contact member having a tubular cylindrical shank projecting through said hole with its head disposed in the counterbore; a metal sleeve telescoped over the tubular shank of the contact member and bearing firmly against the insulated head; and a wire having its end portion received in the tubular shank, said sleeve, tubular shank and wire having portions thereof transversely deformed into interfitting, substantially oval shaped sections so that said parts are secured against relative movement and the contact member is held assembled with the terminal head.

4. In an electric switch: a substantially cylindrical body within which the switch mechanism is located, said body having an externally threaded portion and a shoulder; a clamping nut passed over the inner end of the body and threaded on said threaded portion to cooperate with the shoulder in mounting the switch on a panel; an insulated terminal head closing the inner end of the body, said terminal head having spaced holes therethrough; stationary contact members having tubular shanks projecting through said holes but with all parts thereof lying well within the circumference of the cylindrical body; means to prevent pulling the contact members out through said holes, the inner ends of the contact members providing the stationary contacts of the switch; wire leads having bare end portions received in the tubular shanks of the stationary contact members; and sleeves telescoped over said shanks of the contact members and bearing firmly against the outer face of the terminal head, said sleeves, tubular shanks and wires having portions thereof transversely clinched into mutually interlocking condition to secure said parts together and fix the contact members to the terminal head with all portions of the assemblies lying well within the circumference of the switch body so that the nut may be applied and removed after the wires are secured in place.

5. A combination stationary contact and terminal comprising: an insulated terminal head having a hole therethrough; a tubular pin member received in the hole; a head on one end of said pin member engaging the terminal head at one side thereof to limit movement of the pin member axially in one direction; a metal sleeve

telescope onto the tubular pin member with one end bearing firmly against the other side of the insulated head and its other end portion projecting beyond the pin member; an insulated wire having a bared end portion disposed within the tubular pin member with its insulation entering the metal sleeve; said sleeve, tubular pin mem-

ber and wire being transversely deformed at a localized area to clinch said parts into mutually interlocking relationship and secure the pin member to the terminal head, and the outer extremity of the sleeve being clinched inwardly to grip the insulation of the wire.

EDWARD N. JACOBI.
